FLEXIBLE DISPENSING CLOSURE CAP

Joseph Mart, Beverly Hills, Calif.

Application August 10, 1959, Serial No. 57,123

Term of patent 14 years

(Cl. D58—26)

FIG. 1.

FIG. 2.

FIG. 3.

FIG. 4.

FIG. 5.

FIG. 6.

Fig. 1 is a top plan view of a flexible dispensing closure cap in open position embodying my new design;

Fig. 2 is a side elevational view thereof in open position;

Fig. 3 is a side elevational view thereof in closed position;

Fig. 4 is a rear view thereof in closed position;

Fig. 5 is a front view thereof in closed position; and

Fig. 6 is a bottom plan view of Fig. 3.

I claim:

The ornamental design for a flexible dispensing closure cap, as shown and described.
